(57) **CLAIM**

The ornamental design for a tile, as shown and described.

DESCRIPTION

FIG. 1 is a front, right perspective view of a tile showing my new design;

FIG. 2 is a top, plan view of the tile of FIG. 1;

FIG. 3 is a right, side view of the tile of FIG. 1, the left side being a mirror image thereof;

FIG. 4 is a front view of the tile of FIG. 1, the rear view being a mirror image thereof;

FIG. 5 is a cross-sectional view of the tile taken along line 5-5 in FIG. 2 with the underlying unclaimed structure not being shown for ease of illustration; and,

FIG. 6 is an enlarged view of the tile taken in area 6 of FIG. 5.

The dot-dash boundary line is a boundary line which defines the bounds of the claimed invention. It is understood that the claimed design extends to this boundary but does not include the boundary.

The dot-dash broken lines represent the boundary of a centrally disposed groove, which groove forms no part of the claimed design.

The dash-dash broken lines shown in the drawings, within the boundary lines, are directed to portions of the disclosure which form no part of the claimed design.

The dash-dash broken lines showing each deep groove on the tile and the structure underlying the tile, indicates environmental structure and form no part of the claimed design.

(Continued)

The dot-dot-dash broken lines are showing the circular boundary of the enlargement portions which form no part of the claimed design.

The bottom of the tile is unclaimed.

1 Claim, 3 Drawing Sheets
